WALL DIVIDING BEAD

Attilio C. De Spret, Buffalo, N. Y.

Application May 22, 1933, Serial No. 672,099

11 Claims. (Cl. 72—125)

My invention relates in general to wall dividing beads used in building construction, and more particularly to a bead used between the baseboard and the plaster or stucco of the side wall. It is well known to those skilled in the art that heretofore in some States, the placing of the baseboard beading was put in the terrazzo contractor's specifications. This beading was placed on top of the partly finished baseboard and was held in place in a rather temporary manner while the finishing cement work was put in place. The plaster work was put in place later, and dispute often arose as to the accuracy of alignment of the bead. So as to obviate this difficulty, some States have now put the placing of the base bead in the plasterer's contract, thus putting responsibility for proper alignment upon one contractor.

Under this arrangement, the plaster or stucco work may first be completed before the baseboard is put in, and obviously the baseboard can not be used as a support for the base beading, as heretofore. Some means must, therefore, be provided for securing the beading in place to the studding, tile, or brick of the wall structure. It is well known that under the requirements of some States, the beading must be of bronze or other suitable non-ferrous metal and that due to the cost of such metal, it is not practical to provide an attaching flange of the same material.

The principal object of my invention, therefore, has been to provide a base bead having suitable means for conveniently holding and fastening it in place.

Another object has been to provide a bead which shall be inexpensive to manufacture.

Moreover, my beading is so designed that it may be conveniently secured to any of the structural supports by any of the means employed by building contractors.

Furthermore, my construction is such that bronze or non-ferrous metal may be used for the portion of the beading which is exposed, thus meeting the specification requirements, and a less expensive metal used for the base or holder, with convenient and inexpensive means for securing the strip in the holder.

The above objects and advantages have been accomplished by the device shown in the accompanying drawing, of which:

Fig. 1 is a perspective view of my beading.

Fig. 2 is an enlarged, sectional view, taken on line 2—2 of Fig. 1.

Fig. 3 is a similar sectional view, taken on line 3—3 of Fig. 1.

Fig. 4 shows an enlarged, sectional view showing one method of holding the beading in place on hollow tile.

Fig. 5 is a similar view showing another method of holding the beading in place on brick.

Fig. 6 shows an enlarged, fragmentary, face view, showing another method of holding my beading in place against hollow tile.

My beading comprises a base 10 having two upstanding flanges 11 and 12, being formed by 10 folding the metal back upon itself. The material 13 joining the two walls forms a bottom stop at the base of the channel 14 thus formed. The base 10 is provided with lateral flanges which are formed with a plurality of apertures 16, whereby 15 the beading may be held in place by any one of a number of suitable means, hereinafter described.

The beading strip 20 is of non-ferrous metal such as bronze, and it is placed in the channel 14 20 between the flanges 11 and 12 of the base. The channel may be slightly narrower than the thickness of the beading strip 20 so that it will be frictionally held in place therein. I prefer, however, to form a number of elongated slots 21 in 25 the strip near its inner edge and at such a point that the center of each slot will come about opposite the upper edges of the flanges 11 and 12. After the strip is seated on the bottom wall 13, the edges of the flanges 11 and 12 are forced down 30 into the slots 21 of the strip and thus serve to securely attach the strip 20 to the base 10.

As shown in Fig. 4, where my device is illustrated as being used in connection with a structure having a hollow tile wall 22, the contractor 35 provides a number of holes 23 through the tile where the beading is to be secured by the use of a punch or the like. A wire 24 is then threaded through the holes and one of the ends thereof is brought through one of the slots 21, the ends being brought together and twisted at 25. Before the ends are twisted firmly together, shims 26 are driven under the flanges 15 of the base 10 of the beading in the act of aligning the outer edge 27 of the strip 20. The shims 26 are preferably 40 wedge-shaped so that they may be driven under the flange by tapping, thus providing an accurate method of bringing the edge 27 of the strip the proper distance from the wall. After the beading has been properly aligned, the ends of the 45 wire are firmly twisted together so as to hold the beading and the shims in place while the plastering of the side walls and cementing of the baseboard is being done.

In Fig. 5 I show my invention as applied to a 50

5

30

35

40

45

50

55

brick wall 30. The bricks are drilled with holes 31 at suitable intervals and opposite the place where the beading is to be secured. Wooden plugs 32 are driven into such holes, in a well known manner, and the beading is then fastened in place by large headed nails 33 which are passed through the holes 16 of the flanges 15 of the beading base. The holes 16 are preferably larger than the nails so that adjustment of the beading after initial fastening is thereby made possible. Shims 26 are also employed and when the beading has been properly aligned, the nails are driven tightly in place, thus securely holding the beading.

As shown in Figs. 4 and 5, the outer surface of 15 the completed plastering and the outer surface of the completed baseboard are indicated, respectively, by the dot and dash lines 35 and 36.

Instead of running the wire 24 vertically through the tile and the slots 21 of the beading, 20 the holes 16 in the flanges 15 may be employed and wires 37 passed through such holes and through suitable holes formed in the tile wall, having the wire ends twisted together at 38, as shown in Fig. 6.

25 It will be clear from the foregoing that since the base 10 is of T-shape cross-section, it will be very rigid and that the strip 20 held thereby will be reinforced throughout its length, thus making a wall dividing bead which is very rigid and very 30 easy and convenient to align as well as to fasten in place.

While I have shown my invention as applied to a baseboard beading, it is obvious that it may be used in any position where a gauge is desirable 35 or necessary in plastering or cement work.

From the foregoing it will be clear that when either plaster or cement is applied to the wall and strip, it will pass into the indentations or slots 21 and will thus increase the bond of such plaster 40 and cement with the strip.

Obviously, instead of the slots or holes 21 extending clear through the strip 20, a longitudinal groove or a series of indentations in the surfaces of the strips may be provided and substantially 45 the same results accomplished. Furthermore, the strip may have its inner edge split or slotted, and the legs thus formed spread so as to resiliently hold the strip within the channel 14 formed between the flanges 11 and 12 of the base, or the 50 strip may be welded, soldered or otherwise fastened to a flat base piece. These and other modifications of the details herein shown and described may be made without departing from the spirit of my invention or the scope of the appended 55 claims, and I do not, therefore, wish to be limited to the exact embodiment herein shown and described, the form shown being merely a preferred embodiment thereof.

Having thus described my invention, what I 60 claim is:

1. A wall dividing bead comprising a base formed from a single piece of material and having lateral base flanges and two upstanding, interspaced flanges, a beading strip of non-ferrous 65 metal disposed between the upstanding flanges of the base, the beading strip being formed with indentations, said upstanding flanges being forced down into said indentations at a number of points to securely fasten the strip in place.

70 2. A wall dividing bead comprising a base formed from a single piece of material and having lateral base flanges and two upstanding interspaced flanges, apertures formed through the base flanges, and a beading strip of non-ferrous 75 metal disposed between the upstanding flanges

and formed with a plurality of slots, the outer edges of the upstanding flanges being forced toward each other and into the slots of the strip, whereby the strip is securely held within the base.

3. A wall dividing bead comprising a base having upstanding, interspaced flanges arranged at substantially right angles to the base, and a beading strip of non-ferrous metal formed with indentations near its inner edge and disposed between the upstanding flanges of the base, the upper edges of the flanges being forced down into the indentations to rigidly hold the strip in place within the base, the indentations forming an additional bond with the plaster of the wall.

4. A wall dividing bead comprising a base having upstanding, interspaced flanges arranged at substantially right angles to the base, and a beading strip of non-ferrous metal formed with a plurality of slots and disposed between the upstanding flanges of the base, the upper edges of the 20 flanges being forced down into the slots to securely hold the strip in place within the base, the slots in the strip and indentations in the flanges forming an additional bond with the plaster of the wall.

25 5. The combination with a building wall, of a wall dividing bead, comprising a base having upstanding, interspaced flanges arranged at substantially right angles to the base, a beading strip of non-ferrous metal formed with a plurality of 30 slots and disposed between the upstanding flanges of the base, the upper edges of the flanges being forced down into the slots to securely hold the strip in place within the base, the slots in the strip and the indentations in the flanges forming an additional bond with the plaster of the wall, and means engaging with some of said slots and the building wall for fastening the strip to the wall.

6. The combination with a building wall, of a 40 wall dividing bead, comprising a base having lateral flanges and upstanding, interspaced flanges arranged at substantially right angles to the base, a beading strip of non-ferrous metal formed with a plurality of slots and disposed between the up- 45 standing flanges of the base, the upper edges of the flanges being forced down into the slots to securely hold the strip in place within the base, the slots in the strip and the indentations in the flanges forming an additional bond with the plas- 50 ter of the wall and means for adjusting and holding the dividing bead so that the outer edge of the beading strip is in proper position and alignment.

7. The combination with a building wall, of a 55 wall dividing bead, comprising a base having an attaching flange and an upstanding bead flange at substantially right angles to the attaching flange, a beading strip of non-ferrous metal, means for securing said bead to said base, and 60 means for adjusting and holding the dividing bead so that the outer edge of the bead is in proper position and alignment.

8. A wall dividing bead comprising a beading strip of non-ferrous metal, and a base of inferior 65 metal, the base being formed with lateral flanges, flush with the back surface thereof, and, on the front surface thereof, with two interspaced resilient flanges extending forwardly from the base and arranged at substantially right angles there- 70 to, the strip being rigidly held between said re- sili-ent flanges.

9. A wall dividing bead comprising a base formed of a single piece of inferior metal and having lateral base flanges, flush with the back 75

surface of the base, and, on the front surface thereof, with two interspaced resilient flanges extending forwardly from the front surface of the base and arranged at substantially right angles thereto, a beading strip of non-ferrous metal disposed between the resilient flanges of the base, and means for rigidly securing the base and strip together.

10. The combination with a building wall, of a wall dividing bead, comprising a base of inferior metal having an attaching flange, flush with the back surface thereof, and, a bead flange extending from the front surface of the base and at substantially right angles to the attaching flange, a

beading strip of non-ferrous metal, and means for securing said bead to said base.

11. The combination with a building wall formed of a terrazzo base-board and plaster, of a wall dividing bead arranged between the base-board and the plaster comprising a substantially flat base of inferior metal having its back substantially flush, said base being arranged substantially parallel to the face of the wall, and a beading strip of non-ferrous metal arranged at substantially right angles to the base, and means for securing said strip to said base.
